UNITED STATES PATENT OFFICE.

JAMES W. BALLARD AND HARVEY L. FISHER, OF TOLEDO, IOWA.

RAILROAD-SCALES.

SPECIFICATION forming part of Letters Patent No. 434,056, dated August 12, 1890.

Application filed December 20, 1889. Serial No. 334,348. (No model.)

To all whom it may concern:

Be it known that we, JAMES W. BALLARD and HARVEY L. FISHER, citizens of the United States, residing at Toledo, in the county of 5 Tama and State of Iowa, have invented new and useful Railroad-Scales, of which the following is a specification.

Our invention relates to improvements in railroad-scales, and has special reference to 10 the devices for which Letters Patent No. 398,824 were granted to us March 5, 1889.

The object of our present invention is to provide improved means for operating the rock-shafts, whereby the platform or track-15 rails of the scales may be more easily and positively raised and lowered; and it consists in certain novel features hereinafter described and claimed.

In the accompanying drawings, Figure 1 is 20 a side view, with a part broken away, of a railroad-scale provided with our improved devices. Fig. 2 is a cross-section of the same on the line $\alpha\alpha$ of Fig. 1. Fig. 3 is an enlarged side view of the rack-bars and their connections. Fig. 4 is an enlarged view of the brake, 25 showing the manner of operating the same. Fig. 5 is a perspective detail view.

In our improved scale the base-beams A A are of the usual construction and the rock-30 shafts B are supported in suitable bearings E on the said beams in the manner shown in our former Letters Patent above referred to. The lower members C of the hinged levers in our present device are made somewhat heavier and wider than in our former patented device and are provided with the inclined shoulders D, which are adapted to engage the upper edges of the bearings E, in which the rock-shafts are journaled, so as to prevent the 35 rock-shafts being carried too far to one side or the other, and also to furnish a firm and strong support for the upper members of the lever. Said upper members, which are designated E², are mounted at their upper ends 40 in bearings B² upon the under side of the platform P², and they are provided with the curved pins P³, extending through lugs L³ upon the lower members and having springs S³ coiled thereon in the manner and for the 45 purposes set forth in our previous patent, to which reference has been made above. These 50

features, however, are not claimed as a part of the present invention.

The rock-shafts are provided near one end with the crank-arms F, which project upward 55 from the said shafts, as shown, the lower crank-arms employed in our former device being dispensed with. The upper ends of the crank-arms are connected by the pitmen G, which have their ends pivoted to the upper 60 ends of the crank-arms, and if the crank-arms should be of such a number as to require it intermediate points of the pitmen may be pivoted thereto. The innermost crank-arms F have the sliding bars H pivoted to 65 their upper ends, and these bars have their inner ends extended past each other and provided on their opposing faces with rack-teeth I, as clearly shown.

Below the platform, at the center of the 70 scales, we erect the pair of standards J, in which a shaft K is journaled, and between which standards the ends of the bars H are inserted. A pinion L is secured on the shaft K between the standards J, and this pinion 75 is engaged by the rack-teeth I on the ends of the bars H, so that when the said shaft K is rotated the bars will be simultaneously moved longitudinally and the rock-shafts operated to raise or lower the platform. Rollers M 80 are arranged between the standards J, above and below the bars H, and bear on the said bars so as to hold them to the pinion and at the same time reduce the wear of the parts to a minimum.

A transverse shaft N is arranged on the beams A below the weighing-platform and parallel with the shaft K, and is geared to the said shaft K by means of a sprocket-pinion O on the shaft N, a sprocket-wheel P on the end of the shaft 90 K, and a sprocket-chain Q, connecting the said wheel and pinion. The end of the shaft N projects beyond the side of the platform and under the casing for the scale-beam, and a pinion R is secured on said shaft. A shaft 95 S is mounted transversely in the casing for the scale-beam, and is connected with the pinion R by a chain T, passing over the said pinion R, and a suitable pinion on the shaft S. The end of the shaft S projects beyond the 100 side of the casing, and the operating-wheel U is secured on the said end of the shaft. A

brake-lever V is pivotally mounted below the said operating-wheel, and it is provided at one end with a shoe W, adapted to bear against the said wheel, and its other end is 5 connected with the sliding bars H by a chain X, as shown.

When it is desired to weigh a car, the operating-wheel U is rotated so as to impart motion to the transverse shaft N and the 10 wheel P, so that the pinion K, meshing with the rack-teeth I, will be rotated, and thereby draw the bars H outward, consequently rotating the rock-shafts B, so that the hinged levers will be released from their bearings on 15 the under side of the platform, so that the platform will be lowered onto its pivots and the scales operated in the usual manner to weigh the car. As the rack-bars are drawn inward, the chain X will be caused to pull the 20 outer end of the lever V downward, thereby throwing the brake-shoe W up against the wheel U and causing it to bind on the said wheel, so as to prevent movement of the same, and consequently hold the hinged levers in 25 their bent positions and prevent them accidentally engaging their bearings before the car is weighed, and so as also to prevent turning the wheel too far either way.

Our improved device is very simple and 30 can be easily operated. It will be observed that in our present devices we are enabled to dispense with the lower crank-arms and connecting-rods employed in our former device, and are thereby enabled to bring all the parts 35 of the lifting mechanism above the lower timbers of the scale out of the way of any water or ice that may accumulate in the bottom of the pit of the scale and tend to interfere with the successful operation of the scale. 40 By using the gearing shown in the annexed drawings and hereinbefore described we are enabled to raise and lower the platform more easily and positively than by the use of the hand-lever shown in our former patent, and 45 thereby effect a saving of labor and produce a machine which can be operated with certainty.

The brake, it will be observed, is automatic in its operation, so that there will be no liability of the platform rising before the 50 car has been weighed.

Having thus described our invention; what we claim, and desire to secure by Letters Patent, is—

1. In scales of the character described, the 55 combination, with suitable bearings, of the hinged levers having their lower members provided with the inclined shoulders D to abut against the bearings and limit the movement of said levers, substantially as and for 60 the purposes set forth.

2. The combination of the standards J, the rollers M between said standards, the sliding bars moving on said rollers and provided with rack-teeth in their opposing sides, the 65 pinion engaging said teeth, mechanism for rotating said pinion, the rock-shafts, and connections between the rock-shafts and the sliding bars, as set forth.

3. The combination of the rock-shafts, the 70 sliding bars connecting therewith, the transverse shaft N, the pinion K, adapted to operate the sliding bars, gearing between said pinion and the shaft N, the driving-wheel gearing between said wheel and the shaft N, 75 and the brake-lever arranged below the driving-wheel and adapted to bear thereon and connected with the sliding bars, as set forth.

4. The combination of the rock-shafts, the 80 sliding bars connected therewith, the operating-wheel U, gearing between said wheel and the sliding bars, the brake-lever pivoted below the wheel U and having a shoe at one end adapted to bear against the said wheel, and the chain connecting the opposite end of 85 the lever with the sliding bars, as set forth.

In testimony that we claim the foregoing as our own we have hereto affixed our signatures in presence of two witnesses.

JAMES W. BALLARD.
HARVEY L. FISHER.
